UNITED STATES PATENT OFFICE.

LELAND L. SUMMERS, OF CHICAGO, ILLINOIS.

COKING PROCESS.

1,114,065.

Specification of Letters Patent. Patented Oct. 20, 1914.

Application filed May 13, 1913. Serial No. 767,857.

To all whom it may concern:

Be it known that I, LELAND L. SUMMERS, a citizen of the United States, and residing at Chicago, in the county of Cook and State 5 of Illinois, have invented certain new and useful Improvements in Coking Processes, of which the following is a specification.

The object of my invention is to provide a process of coking by means of which an improved fuel may be produced. My process 10 is particularly adapted to coals of high oxygen content and of high volatile content, which are difficult to treat in the ordinary processes.

Generally speaking, my improved process 15 is carried on in a retort such as shown in my Patent No. 951,786, in which coal is fed to the retort at one end and conveyed therethrough, the heat being applied from the 20 top so that the products of distillation arising from the carbonaceous material pass toward the source of heat.

With these objects in view, my invention 25 consists in the features hereinafter described and claimed.

In the drawings, Figure 1 is an elevation, partly in section, of a retort showing one way in which my process may be carried out. Fig. 2 is a cross section of the retort on the 30 line 2-2 of Fig. 1. Fig. 3 is a plan view, partly in section, of the retort, on the line 3-3 Fig. 1. Fig. 4 is a view similar to Fig. 1, showing a modified arrangement.

Referring to the drawings, Fig. 1 shows a 35 retort through which the carbonaceous material is conveyed on a reciprocating floor 2, actuated by a ram 3, the carbonaceous material being fed to the retort from the bin 1.

The carbonaceous material in passing 40 through the retort is subjected to the action of an external source of heat, provided by the overhead heating ducts 4 in the arch and this carbonaceous material, after being conveyed through the retort, is discharged into 45 the hopper 5, all as more fully shown and described in my Patent No. 951,786, March 8th, 1910.

The overhead heating ducts may be heated 50 with producer gas, excess oven gas, or directly by a furnace as may be desired.

As shown in Fig. 3, there is arranged at a suitable point a means for withdrawing the hot gases from the oven, consisting of a duct 10 leading from the oven to a recuperator 15 whence they pass through pipe 15^a to the condenser 16, the exhauster 17, returning 55

through the recuperator and the duct 17^a to the ducts 6, arranged in the arch. From the ducts 6, the gases pass through the movable pipe 18, fitted with the stuffing box 20, and are thus connected with inlet ducts 7 arranged on the floor of the conveyer. As shown in Fig. 1, these inlet ducts are provided with nozzles 8 and the ducts have a common header 9, connected with the inlet pipe 18. The gases heated to the desired temperature by their passing through the ducts 6 issue through the nozzles 8 in the duct 7 and then rise and distribute through the cool portion of the carbonaceous material, intermediate the freshly charged material and the more highly heated portions thereof. The gases pass through this portion of the carbonaceous material at a temperature of about 800 degrees to 900 degrees Fahrenheit. This admission of hot gas results in a more uniform heating of the carbonaceous material at this point than is obtained when the heat is derived from the overhead arch only. There is consequently a more perfect distillation of the richer hydrocarbons at this point, the resulting distillate containing a large amount of rich tar and also a maximum amount of rich hydro carbon gases such as methane, ethane, etc. By the mixing of the hot gases with the gases being distilled, the distillate products are diluted and the rich tars are protected from decomposition. A further result of this uniform heating of the carbonaceous material is that the carbonaceous material at this point assumes the plastic condition more uniformly so that there will be in the retort, first, the freshly charged material, second, a section of material in the plastic condition, and beyond this, approaching the discharge end of the oven, the more completely coked material.

As the reciprocal floor is alternately advanced and withdrawn to feed fresh material into the oven, there results a compression of the material. The material already in the oven being held from backward movement, as described in my former Patent No. 951,786, so that that portion of the material which is in the plastic condition is highly compressed, resulting in a denser coke.

If desired, the ducts 7, Fig. 1, may be extended farther into the oven as indicated at 7^a and provided with nozzles 8^a connected externally through a separate inlet pipe 9^a Fig. 3, with an independent heater 21, through which a portion of the hot gases

may be withdrawn through the pipe 21^a. These gases being highly heated may be passed through the more highly heated portions of the coking material and at a temperature sufficient to cause a final distillation from this material, the by-products resulting from this distillate may be withdrawn through a suitable outlet pipe 23. The products from the distillate at the lower temperature being withdrawn through the pipe 24.

In Fig. 4, I have shown a slightly modified form of oven for carrying out my process in which the heating ducts 7 are not connected externally, but extend throughout the retort and are provided near the discharge end with nozzles 14 and near the charge end with nozzles 8 as before described. The center portion of the conveyer floor at 13 is slightly elevated so that the carbonaceous material at this point will be densely packed, separating the charge and discharge portions of the retort.

The hot gases are inserted into the oven from the pipe 12 connected with the recuperator and pass in contact with the incandescent arch and downward through the nozzles, any suitable suction devices being provided for this purpose. These gases then pass toward the charge end of the retort, through the duct 7, and are discharged through the nozzles 8 upward through the cooler portion of the carbonaceous material, causing the distillation of the volatile products of the coal as before described, the distillate being withdrawn through the oven through the outlet 24.

In each of these forms of my invention the carbonaceous material entering the retort from the bin 1 and being carried forward by the reciprocating floor of the oven 2 is subjected to the action of the hot gases from the nozzles 8. After having distilled from it the tar and rich hydro-carbons, the carbonaceous material in a plastic condition is compressed by the operation of the conveyer floor 2, and this compressed plastic material is carried forward and subjected to further heat action, either from the hot gases entering by means of the nozzles 8 or by the descending current of hot gases, the eventual result being to further distil the products from the compressed carbonaceous material, which is subsequently discharged into the hopper 5 at the discharge end of the oven.

The advantages of this process are that when applied to a continuous coking process where the charge of coal is moved continuously forward toward hotter portions of the oven or retort, an improved character of coke may be obtained as the circulation of gas through the coal may be at a low enough temperature to give a maximum yield of tar and other rich hydrocarbons

and the coal may be caused to assume a plastic condition by proper adjustment of the temperature. While this plastic condition exists, the coal may be compressed so that a fuel of great density may be formed and subsequently this fuel is moved forward into a hotter portion of the oven or retort, and the remainder of the volatile matter, or any portion desired, may be distilled by the higher temperature. This final distillation may be accomplished by the direct heating of the retort or by increasing the temperature of the circulating gases to such an extent as to cause the direct volatilization of the hydrocarbons remaining in the compressed fuel, or of any desired portion of them. The resulting fuel obtained will then be a compressed coke in which there remains the desired quantity of volatile matter but which has been caused to assume a dense form by means of the compression while in a heated condition, and a hardening of the fuel by the subsequent distillation to the desired extent of the volatile products from the carbonaceous material.

Further advantages of this process are that in the low-temperature distillation of coal it is possible to recover valuable lighter hydrocarbons which are distilled off only at low or moderate temperature and by maintaining a moderate temperature during the period they are distilled, decomposition of the products is prevented. In any external heating of the retort, the first action is the heating of the portions of fuel adjacent to the retort, there being a considerable time element involved in the transmission of the heat from the portions adjacent to the walls of the retort toward the unheated portions of the fuel, the general tendency being to first form a hard coke next to the heated surface while the unheated coal in the more remote portions of the charge has not reached a plastic condition. There will, therefore, be the condition of a hard coke, plastic semi-coke, and an unheated coal, making it more difficult to uniformly compress the charge, or to produce a uniformly heated material. Likewise the volatile matter distilled from the charge will vary in its composition with the varying temperature of the charge. When a heating medium such as a highly heated gas is inserted into the cooler portion of the charge and caused to distribute through the charge toward the zone of heat, a uniform heating of the material will result, and the lower volatile hydrocarbons may be distilled at practically the temperature at which they are liberated and the decomposition of the lighter products will be a minimum. In the distillation of coal at low temperatures, a portion only of the volatile matter is driven off, and this portion contains the richest tar and the richest hydro-

carbon gas; at this temperature, however, there is a very low yield of ammonia. There is a distinct advantage in subsequently heating the material to a higher temperature in order to recover this valuable by-product. In the recovery of ammonia, it is very essential that hydrogen in a free state be circulated in intimate contact with the coal at a sufficient temperature to release the 10 ammonia from the organic compounds of the carbonaceous material. It is, therefore, preferable to circulate a gas through the carbonaceous material containing free hydrogen in order that the ammonia yield may 15 be a maximum as otherwise the nitrogen simply combines with itself to form an inert molecule of nitrogen which is without value. In the presence of heated carbonaceous material hydrogen will unite freely with the 20 nitrogen and will greatly increase the yields of ammonia.

While I have described a specific way in which my process may be carried out, it is to be understood that I do not intend to be 25 limited to such specific methods, as my improved process may be carried out in other ways.

I claim:

1. The herein described process which 30 consists in feeding carbonaceous material to an externally heated closed retort, inserting gases heated to a point sufficient to cause the carbonaceous material to assume the plastic condition into the freshly

charged portion of the material, causing 35 the gases to travel through the freshly charged material toward the source of heat, and conveying the material through the retort.

2. The herein described process which 40 consists in feeding carbonaceous material to an externally heated closed retort, inserting into the freshly charged portion of the material hot gases taken from a more fully coked portion of the material nearer the 45 discharge end of the retort, causing said gases to travel through the freshly charged portion of the material toward the source of heat, and conveying the material through the retort.

3. The herein described process which 50 consists in feeding carbonaceous material to a closed retort heated so as to cause the products of distillation to pass toward the source of heat, further heating an intermediate portion of the material between the freshly charged material and the more fully coked portion of the charge to cause the intermediate portion to assume a uniform 55 plastic condition and then compressing the 60 intermediate portion between the freshly charged material and the more fully coked portion of the charge.
